UNITED STATES PATENT OFFICE.

GEORGE W. NEVILL, OF RICHMOND, VIRGINIA.

IMPROVEMENT IN DITCHING-MACHINES.

Specification forming part of Letters Patent No. 136,752, dated March 11, 1873.

To all whom it may concern:

Be it known that I, GEORGE W. NEVILL, of Richmond, in the county of Henrico and State of Virginia, have invented certain Improvements in Ditching-Machines, of which the following is a specification:

The invention relates more particularly to the ditching-machine patented by me on the 30th of January, 1872, although the improvements are adapted to all ditchers of a construction in certain respects similar. The present invention consists in means for enabling the vehicle to turn in a small circle at the end of ditch, or when it becomes necessary, after cutting one layer of earth to return and cut another; also, in means for enabling the flanged soil-carrying wheel to adjust itself, both laterally and vertically, in an easy and unimpeded manner to the inside of the ditch; and, finally, in means for supporting the ditching-wheel frame in its true position, while the front axle may move independently of it, and vice versa.

In the drawing, Figure 1 is a side elevation with parts broken out. Fig. 2 is a top view with the seat and cross-bar removed. Fig. 3 is a detail view of the rests. Figs. 4 and 5 are detail views of the lever-frame and the bearing.

A represents an axle provided with wheels a a , hounds a' a' , cross-bar a^2 , and the seat a^3 . B is the frame of a ditching-machine in which rotates, by contact with the earth, the flanged wheel and earth-carrier C. The parts that co-operate with said wheel in cleaning and discharging dirt therefrom, and in cutting and transferring the soil, are fully described in my patent of January 30, 1872. In using the said patented machine I have found great objection to exist to the old modes of turning, on account of the great space and loss of time required.

In order to remedy this difficulty I place a swiveled wheel, D, in the rear of flanged wheel C in a lever-frame, E, which has a locking-pin, e, that fits into a notch of frame. F F are rods placed one on each side of the frame B, each provided with a stop or eye, f, and each pivoted to the axle A. f^2 are loops appended to an overhung bar and forming rests which support loosely the rods F F when these rods are not in the hooks f^1 attached to side of bracket f^4 or of frame B. G is a frame, pivoted to axle of wheel C and union-jointed to a vertical stud, g, on axle A. The effect of this mode of connecting the flanged wheel C

with the front running-gear of the vehicle is to allow the said wheel to adjust itself vertically and laterally in the ditch, although the horses and front wheels may deviate considerably from their true relative position to the flanged wheel. H is a bar pivoted near the top of frame B and working in the slot i of a post, I. This post is journaled in the front running-gear, so as to allow the latter to turn laterally upon it, while the pivoted bar H allows of the vertical motion either of the tongue or frame B.

The object of this bar-connection is to relieve the frame G of a large part of the torsional or lateral strain, and to hold the wheel C with inclosing frame firmly and securely in position.

The operation of this device is as follows: While traveling over the ditch the rods F F remain loosely in the rests f^2 of bar, so that the tongue will be allowed proper lateral play, while the lever-frame E is locked to its supporting-bracket f^4 by pin e. When, however, the machine arrives at the end or turn of the ditch the frame E is unlocked from the bracket f^4 and turned by hand until at right angles to the frame B. The rods F F then lock axle A by means of the hooks and eyes f^1 , so that said axle cannot turn. The horses are then turned on the smallest possible half-circle, the wheel upon the turning side forming the center about which the whole machine moves. When the semicircle is completed the machine has exactly reversed its position over the end of ditch, and is ready to be moved back and made to take another rectangular piece of soil below the one just taken out.

Having thus described my invention, what I claim as new, and desire to secure by Letters Patent, is—

1. The rear wheel D, placed in a swiveled and lock lever frame E, in combination with the rods F F pivoted to the axle and made to lock to the frame B or bracket f^4 , as and for the purpose set forth.

2. The frame G pivoted at one end to the axis of the ditching-wheel C and at the other to the axle A, as and for the purpose described.

3. The bar H pivoted to the frame B and working in the slot of the swiveled post I, as and for the purpose described.
